UNITED STATES PATENT OFFICE

132,776

DESIGN FOR A BADGE OR SIMILAR ARTICLE

Ethel S. Crittenden, Houston, Tex.

Application January 15, 1942, Serial No. 105,215

Term of patent 7 years

To all whom it may concern:

Be it known that I, Ethel S. Crittenden, a citizen of the United States residing at Houston, in the county of Harris and State of Texas, have invented a new, original, and ornamental Design for a Badge or Similar Article, of which the following is a specification, reference being had to the accompanying drawing, forming a part thereof.

I claim:

The ornamental design for a badge or similar article, as shown.

ETHEL S. CRITTENDEN.
